The ornamental design for a trigger sprayer head, as shown and described.

DESCRIPTION

FIG. 1 is a front, right side perspective view of a trigger sprayer head showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof, on an enlarged scale;

FIG. 7 is a sectional view thereof taken along lines 7—7 of FIG. 2;

FIG. 8 is a front, right side perspective view of a second embodiment of the trigger sprayer head showing my new design;

FIG. 9 is a left side elevational view thereof;

FIG. 10 is a right side elevational view thereof; and,

FIG. 11 is a front elevational view thereof.

The broken lines showing the containers below the trigger sprayer heads of FIGS. 1-11 are for the purpose of showing environmental structure only and form no part of the claimed design. The rear elevational view, the top plan view, and the sectional of the alternative embodiment of FIGS. 8-11 are omitted as being identical to FIGS. 5, 6, and 7 of the first sprayer head embodiment.
